CLAIM

The ornamental design for a memory card adapter, as shown and described.

DESCRIPTION

FIG. 1 is a front perspective view of a memory card adapter of the invention;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken line drawing in FIGS. 1, 2, 4, 5 and 7 is for illustrative purposes only and forms no part of the claimed design.
